UNITED STATES PATENT OFFICE.

JOEL W. PERKINS, OF EAST HAMPTON, CONNECTICUT.

MECHANICAL TOY.

SPECIFICATION forming part of Letters Patent No. 279,275, dated June 12, 1883.

Application filed November 29, 1882. (No model.)

To all whom it may concern:

Be it known that I, JOEL W. PERKINS, of East Hampton, in the county of Middlesex and State of Connecticut, have invented certain 5 new and useful Improvements in Mechanical Toys, of which the following is a description, reference being had to the accompanying drawings, where—

Figure 1 is a side view of a mechanical toy embodying my said improvements. Fig. 2 is a view much the same as Fig. 1, but with parts in section, so as to show the operating mechanism.

The apparatus is one designed to represent 15 Punch and Judy.

The letter *a* denotes the frame. The letters *b* denote one set of wheels, and the letters *c* denote the other set of wheels. The wheels *c* are fast with the cranked shaft *d*, from which 20 a pitman, *e*, runs to the seesaw *f*, on which is a figure of Punch, denoted by the letter *g*, (and there may be a bell, as shown, under Master Punch.)

The wheels *c*, in operating, cause the figure

of Punch to seesaw, and to apparently beat 25 the head of Judy with the rod that Punch holds in his hands. The wheels *b* are fast on the cranked shaft *h*, from which a pitman, *i*, runs to the figure of Judy, (denoted by the letter *j*,) causing Judy to rise and fall with the 30 rotation of the wheels *b*. When Judy is down she is hidden within the screen *k*, which is an adjunct of the frame *a*, and as Judy rises her head projects above the screen, so as to be seen.

I claim as my improvements—

1. In combination, the frame *a*, bearing screen *k*, the wheels *c*, the cranked shaft *h*, pitman *i*, and the figure *j*, all substantially as described, and for the purpose set forth.

2. In combination, the frame *a*, the wheels 40 *b* and *c*, cranked shafts *d* *h*, pitmen *e* *i*, seesaw *f*, and the screen *k*, all substantially as described, and for the purpose set forth.

JOEL W. PERKINS.
